JAMES GILFILLAN, OF CHARLESTOWN, MASSACHUSETTS.

Letters Patent No. 66,233, dated July 2, 1867.

IMPROVEMENT IN WATER-CLOSET VALVE APPARATUS.

The Schedule referred to in these Letters Patent and making part of the same.

TO ALL PERSONS TO WHOM THESE PRESENTS SHALL COME:

Be it known that I, JAMES GILFILLAN, of Charlestown, in the county of Middlesex, and State of Massachusetts, have invented a new and useful Improvement in Water-Closet Valve Apparatus; and do hereby declare the same to be fully described in the following specification, and represented in the accompanying drawings, of which—

Figure 1 is a vertical section of such apparatus.

Figure 2 is a top view, and

Figure 3 a side elevation of the valve stem and its valves.

The purpose of the apparatus, on which my improvement is applied, is to allow the valve of the supply pipe of a water-closet to gradually close upon or move towards its seat after having been moved off the same, the same being to obtain the necessary flowage of water to effect the cleansing of the pan or basin of the closet.

The valve is usually moved off its seat by means of a lever, which, after having been pulled up by a handle attached to it, is suddenly allowed to fall away from the valve-stem. The slow descent of the valve is effected by a vacuum-chamber, and a flexible cup-piston arranged within such chamber. The said vacuum-chamber constitutes the interior of a cylindrical vessel, arranged over and so as to open into the valve case, the cup-piston being arranged within the vacuum-chamber and connected to the valve.

My improvement relates especially to the said piston, which, as heretofore made, has been a cup of leather or vulcanized India rubber or gutta percha. It has been found that the piston so made is liable, after being in use, to become inverted or turned wrong side out within the vacuum-chamber, in which case it will not operate to advantage. In order to prevent the inversion of the valve, I combine with it a flexible spring-cap made of metal, and being elastic at its edge or periphery, and cup-shaped. This cap I construct of a very thin disk of metal, having slits laterally in and through it, from its circumference toward its centre, they being arranged at equal or about equal distances apart. The disk, after being so formed with slits, is to be bent in the shape of a cup, in which case the portions next its circumference will be caused to lap on one another, and the whole will constitute a concavo-convex spring to receive and fit to the flexible piston, whose edge should extend below that of the said cap a short distance. The metallic spring-cap so made will contract and expand with the rubber or flexible piston, and will prevent it from becoming inverted while they may be in use.

In the drawings, A denotes the valve-case, of which *a* is the valve-seat, and *b* and *c* the induction and excretion passages. B is the valve-stem provided with a valve, *o*, and the flexible cup-piston *d*, made of gutta percha, leather, India rubber, or the equivalent thereof. C is the vacuum-chamber situated over the valve-chamber, and to operate with the flexible piston. D is the metallic, elastic, or spring-cap, made as described, and fixed upon the valve-stem concentrically therewith, and with respect to the flexible piston in manner as represented in fig. 1. A helical spring, E, is arranged within the vacuum-chamber and presses against its stop, and also against the elastic cap D, the purpose of such spring being to effect the closing of the valve or its movement towards its seat. This movement of the valve will be resisted by the vacuum in the chamber C. While the valve is in the act of being forced off its seat the piston will be driven upward in the vacuum-chamber, and the piston downward, the water, in the mean time, passing the periphery of the piston and entering the vacuum-chamber. My improved arrangement of the spring, viz, in the vacuum-chamber, prevents it from becoming clogged by chips, or other extraneous matter carried into the apparatus with the water while passing through it.

I claim the combination of the elastic metallic concavo-convex cap D with the flexible cup-shaped piston *d*, applied to the valve-stem B, and arranged within the vacuum-chamber C, as and for the purpose specified.

I also claim the arrangement of the spring E within the vacuum-chamber and with respect to the piston, as set forth.

JAMES GILFILLAN.
